CLAIM

The ornamental design for a side table, as shown and described.

DESCRIPTION

FIG. 1 is a front elevational view of a side table showing my new design;

FIG. 2 is a rear elevational view thereof;

FIG. 3 is a left side view thereof;

FIG. 4 is a right side view thereof;

FIG. 5 is a top plan view thereof;

FIG. 6 is a top, front, right side perspective view thereof;

FIG. 7 is a top, rear, right side perspective view thereof;

FIG. 8 is a top, front, left side perspective view thereof;

FIG. 9 is a top, rear, left side perspective view thereof;

FIG. 10 is a top, front, right side perspective view thereof shown in an alternative configuration of use; and,

FIG. 11 is a top, front, left side perspective view thereof shown in an alternative configuration of use.

The broken lines illustrate portions of the side table that do not form part of the claimed design.
